ELECTRICALLY OPERATED VALVE

John Harding, Jr., Dallas, Tex.

Application February 14, 1944, Serial No. 522,367

2 Claims. (Cl. 137—139)

1

This invention relates to electrically operated valves.

An object of this invention is to provide a substantially balanced valve which is so constructed and arranged that the valve may be moved to open position against high pressure with a small solenoid.

Another object of this invention is to provide in a valve of this type a spring-pressed latch for holding the valve in open position and a solenoid operator for moving the latch to released position.

To the foregoing objects and others which may hereinafter appear, the invention consists of the novel construction, combination and arrangement of parts as will be more specifically referred to and illustrated in the accompanying drawings wherein embodiments of the invention are shown, but it is to be understood that changes, modifications and variations may be resorted to which fall within the scope of the invention as claimed.

In the drawings:

Figure 1 is a detail top plan of a solenoid valve constructed according to an embodiment of this invention,

Figure 2 is a sectional view taken on the line 2—2 of Figure 1,

Figure 3 is a fragmentary vertical section showing the valve in open position,

Figure 4 is a sectional view taken on the line 4—4 of Figure 2.

Referring to the drawings, numeral 10 designates generally a valve housing formed of a body 11 provided with an intake boss 12 for connection to a source of fluid pressure supply and an outlet boss 13 which, in the present instance, is in alignment with the intake boss 12. A valve seat 14 is disposed within the body 11, the valve seat being of an annular configuration and formed on the upper side of a vertical wall 15 adjacent the inner end of the boss 12 and having a length less than the diameter of the bore of the body 11 so that the fluid may pass through the opening 16 above the seat 14. The seat 14 is also carried partly by a depending wall 17 which is disposed inwardly of the boss 13, the lower end of the wall 17 being spaced from the bottom of the body 11, thereby providing a passage 18 for permitting the fluid to move from the passage 16 through the valve seat 14 and the passage 18 into the outlet boss 13.

An upstanding cylindrical boss 19 extends upwardly of the body 11 and concentrically of the valve seat 14. The boss 19 is formed with a

2

cylindrical bore 20 within which a piston-type valve member generally designated as 21 is adapted to slidably engage. The valve member 21 includes a lower head 22 and a cylindrical skirt 23. The skirt 23 is slightly less as to its outer diameter than the inner diameter of the cylinder or bore 20, thereby providing a leak joint 24 which communicates with the intake boss 12 and permits the cylinder 20 and the open upper side of the piston 21 to be maintained filled with fluid at all times.

The provision of the leak joint 24 provides for pressure of fluid on the upper side of the valve member 21 in order to maintain the valve member 21 in normally closed position. The head 22 of the piston 21 is formed with an annular groove 25 within which a ring-shaped resilient sealing member 26 is adapted to be seated. When the valve member 21 is in closed position, the sealing member 26 engages the seat 14.

The head 22 of the valve member 21 is formed with a central opening 27 through which the reduced inner end 28 of a valve stem 29 is adapted to extend. The head 22 on its upper side is formed with an annular downwardly offset valve seat 30 within which an auxiliary or bleeder valve member 31 is adapted to loosely engage. The bleeder valve member 31 has secured thereto a resilient sealing ring 32 which is adapted to engage on the seat 30. Preferably, the outer diameter of the bleeder valve member 31 is substantially less than the diameter of the recess within which the valve seat 30 is formed so that there will be a space 33 for passage of the fluid from the interior of the valve member 21, past the valve member 31, through the opening 27 and into the outlet side of the valve body 11 when the valve 31 is open. In order to provide for the more rapid filling of cylinder 20 and valve 21, and the rapid emptying of both cylinder 20 and valve 21, valve 21 is formed with a plurality of bleed openings 22a. In the closed position of valve 21, bleed openings 22a communicate with the intake side of the valve housing.

The reduced lower or inner end 28 of the valve stem 29 has secured thereto a plate 34 which is held on the stud 28 by means of a nut 35. A cylindrical sleeve 36 is disposed about the stud 28 and supports the plate 34 in downwardly or inwardly spaced relation with respect to the main valve head, thereby providing a lost motion with respect to the bleeder valve 31 and the main valve member 21. The head 22 on the inner or lower side thereof is formed with a plurality of radially arranged grooves or channels 37 so that when

the plate 34 is in contact with the inner or lower side of the head 22, the fluid may leak past the plate 34 into the space below the valve member 21.

A closure 38 is secured to the upper end of the boss 19 by fastening members 39. A plate 40 is interposed between the inner or lower side of the closure 38 and the top of the boss 19, the latter being preferably rabbeted as at 41 so that the closure 38 will be disposed concentric to the center of the valve seat 14. A gasket or sealing member 42 is interposed between the plate 40 and the upper end of the boss 19. A valve closing spring 43 is disposed within the cylinder 20, bearing at its upper end against the inner side of the plate 40, the latter being formed with an annular bead 44 for holding the spring 43 concentrically within the cylinder 20. The lower end of the spring 43 bears against a cup-shaped plate 45 which is interposed between the upper side of the bleeder valve member 31 and the shoulder formed between the stud 28 and the stem 29.

The stem 29 is sealed within the cylinder 20 by means of a metal bellows 46. The bellows 46 at its upper end is soldered or otherwise firmly secured and sealed to a downwardly extending annular flange 47 formed in the center of the plate 40. The lower end of the bellows 46 is inturned as at 48 and is interposed between the spring retaining plate 45 and the shoulder 49 formed between the stud 28 and the stem 29. The bellows 46 is formed of resilient metal and in its normal unexpanded or noncontracted position the valve member 21 will be in closed position. The spring 43 is of such resiliency as to maintain the valve member 21 against the seat 14 in the closed position.

The valve member 21 is adapted to be moved to an open position by means of a solenoid operator, generally designated as 50. The operator 50 includes a coil 51 mounted in a housing 52 which is secured as by welding or the like to the upper side of the closure 38. A movable core 53 is slidable within the coil 51 being slidably mounted in an inner sleeve 54 within the coil 51. The core 53 may be formed integral with or secured to the upper end of the valve stem 29 and is provided with a substantially conical upper end 55. A top plate or head 56 is mounted on the upper end of the coil 53 and has a plug 57 secured thereto or formed integral therewith which extends interiorly of the sleeve 54. The plug 57 at its lower end is formed with a substantially conical recess 58 within which the conical head 55 of the core 53 is adapted to engage when the latter is moved upwardly at the time the coil 51 is energized.

A shaft 59 which is formed with a threaded stud 60 at the lower end thereof is secured to the core 53 and slidably engages in a guide bore 61 formed in the plug 57 and through the head 56. The shaft 59 at a point intermediate the upper and lower ends thereof is provided with an annular groove or keeper 62. A horizontally shiftable latch 63 which is slidably carried by the head 56 is adapted, when in latched position, to engage in the keeper or annular groove 62 so as to hold the core 53 in its uppermost position and hold the valve member 21 in open position. Preferably, the shaft 59 extends above the top wall 64 of the housing 52 and is provided with a head 65 so that the valve member 21 may be manually moved upwardly to an open position.

The latch member 63 is adapted to be moved to a released position by means of a releasing

solenoid structure 66. The solenoid structure 66 includes a coil 67 having a sleeve 68 centrally thereof within which a plug 69 is firmly secured. The plug 69 is provided with a conical recess in the upper end thereof as indicated at 70 and a solenoid core 71 is slidable in the sleeve 68 and is formed with a conical lower or inner end 72 for engagement in the conical recess 70.

A latch operating spring 73 is mounted in a central opening 74 formed in the plug 69 and also in a central opening 75 formed in the core 71. A stem 76 is fixed to or formed integral with the core 71 and extends above the solenoid structure 66, being provided with a slot 77. A bell crank 78 or latch shifting member 78 is rockably mounted on a pivot 79 carried by a support 80 mounted on the upper end of the solenoid structure 66. The bell crank 78 has one arm 81 thereof engaging within the slot 77 and preferably, a transversely disposed pin 82 extends through the slot 77 for engagement with the upper edge of the arm 81 so as to pull the bell crank 78 downwardly to latch releasing position.

The other arm 83 of the bell crank 78 is loosely mounted in a slot 84 formed in the outer end of the latch 63. A transversely extending pin 85 extends across the slot 84 and is adapted to bear against the outer side of the arm 83 so that when the core 71 is pulled downwardly by energizing the coil 67, the two pins 82 and 85 will engage the adjacent edges of the bell crank 78 and pull the latch member 63 outwardly to a released position. The stem 76 of the core 71 extends upwardly through an opening 86 which is formed in the top wall 64 of the housing 52 in order that the core 71 may be manually moved downwardly to release the latch 63 and permit the valve member 21 to be moved downwardly to closing position under the tension of the spring 43.

A pivoted closure or cap 87 is carried by the top of the housing 52 and encloses the projecting ends of the shaft 59 and the stem 76. In order to provide a means whereby the solenoids 50 and 66 may be alternately placed in an electric circuit for energizing thereof and so that the user of this structure will be able to determine the position of the valve member 21, I have provided a latch operated switch structure, generally designated as 88.

The conductors 92 and 100 are extended from the housing 52 through a coupling member 103 which is fixed to the housing 52 adjacent the solenoid structure 66.

In the use and operation of this valve structure, the intake boss or bushing 12 is connected to the source of fluid supply under pressure and the outlet boss or bushing 13 is connected to the desired part receiving the fluid. When the valve member 21 is in closed position under the tension of the spring 43, the fluid pressure in the boss or bushing 12 will be against the exposed cylindrical side 23 of the valve member 21 which is exposed in the passage 16. The pressure from the intake boss or bushing 12 will pass through the leak joint 24 into the interior of the valve member 21 and the cylinder 20, thereby tending to normally hold the valve member 21 in closed position.

When the coil 51 is energized the core 53 will be raised against the tension of the spring 43 and when the keeper 62 is in alignment with the inner end of the latch 63, spring 73 will move the auxiliary core 71 upwardly and move the latch 63 into engagement with the keeper 62. When the core 53 initially starts on its upward movement,

the bleeder valve 31 will initially be raised from the seat 30 and the space 33 around the bleeder valve 31 is of such size that the fluid within the piston valve member 21 and in the cylinder 20 may flow downwardly through the opening 27 in the center of the valve head 22 at a faster rate than the fluid enters the interior of the cylinder 20 through the leak joint 24. The provision of having fluid in the interior of the valve member 21 and of the cylinder 20 makes it possible to cushion the movement of the valve member 21 to opening position, there being a slight lost motion until the core 53 is able to pull the valve member 21 to a fully open position.

At the time the latch 63 is moved inwardly to latching position the bridging member 95 is moved out of engagement with contacts 89 and 90, breaking the circuit to the main coil 51 and closing the circuit to the releasing coil 67.

When the coil 67 is momentarily energized core 71 will be moved downwardly against the tension of spring 73. The latch 63 will be pulled outwardly by rocking of bell crank 78 and then spring 43 will move the valve member 21 downwardly to closing position. When the latch member 63 is in released position, the inner end thereof is in sliding contact with the side of the shaft or stem extension 59. At the time the valve member 21 moves downwardly to closing position, the bleeder valve 31 first closes and the continued movement of the piston valve downwardly will cause a partial vacuum to occur in the cylinder 20, thereby cushioning the downward movement of the main valve 21. This cushioning movement of the main valve 21 to closing position eliminates any hammering occasioned by quick closing of a valve member.

The partial vacuum generated by downward movement of the valve member 21 is relieved when the valve member 21 is in closed position by leaking of the fluid on the high pressure side of the valve through the leak joint 24, so that the cylinder 20 and the interior of the valve member 21 will be filled with fluid under pressure from the high pressure or inlet side of the valve whenever the valve member 21 is in closed position. The provision of the resilient bellows 46 which seals the stem 29 in the valve housing 10 makes it possible to use a fairly light tension spring 43 for moving the valve member 21 to closed position and the use of the light tension spring also permits the use of a low power solenoid for moving the main valve member to open position.

This solenoid valve structure has been designed particularly for use in airplanes for connecting a selected fuel tank with the engine in order that the pilot may connect the desired tank with the engine by momentarily closing an electric circuit. No electric current is required to hold the valve in either the "open" or "closed" position.

With a valve as herein disclosed, there is provided a structure wherein the valve member is held in closed position by reduced pressure from the inlet side of the valve through the loose coupling between the valve member and the cylindrical bore of the housing, and the filling of the bore with the pilot or auxiliary valve member in closed position will positively lock the main valve member in closed position. Movement of the pilot or auxiliary valve member to open position breaks the fluid lock for the main valve member, and

provides for equalization of pressures on both inlet and outlet sides of the main valve member, so that only a light force is required to move the main valve member to open position.

5 I have discovered that a pilot valve having a diameter slightly greater than the diameter of the effective area or closed end of the bellows, and also slightly greater than the depth of the convolutions of the bellows, will stay closed under varying pressures in the valve housing, and that a solenoid having a pulling force only slightly greater than the expansion force of the valve spring which, in this case, is designated 43 will be required to open the pilot and main valves.

15 The effective area of the pilot valve being proportionately greater than the effective area of the bellows, the fluid pressure in the valve housing will normally maintain the valve closed. The difference between these effective areas can be readily calculated into pounds pressure. The pounds pressure required to contract the valve spring being known and there being added to this latter pressure the calculated difference between the pounds pressure of the effective areas of the bellows and pilot valve, the solenoid can then be calculated and constructed to provide the necessary pull to overcome the entire pressure force.

20 The inside of the bellows is essentially subject to atmospheric pressures, whereas the outside of the bellows is subject to the inlet pressure when the valve is closed, and the line pressure when the valve is open, these inlet and or line pressures being greater than atmospheric pressure. To overcome this pressure differential, the little auxiliary valve 31 has an effective area slightly in excess of that of the effective or flat end area of the bellows. By this means, the little valve 31 can be opened with a relatively light pull, or a pull sufficient to overcome this differential, plus the rating of the spring. Further, with the valve 25 in the open position, the line pressure would have a tendency to keep the bellows in its compressed condition unless the spring was of a sufficient rating to extend the bellows, which happens when the plunger is unlatched and the valve closes.

40 What I claim is:

1. In a valve structure, a housing, a seat in said housing, a valve member engageable on said seat, a spring constantly urging said member toward said seat, and an electro-magnet operator connected to said valve member for moving the latter to open position, said operator comprising a solenoid coil, a core slidably in said coil, means securing said core to said valve member, a stem 45 extending from said core and formed with an annular groove, a latching bar slidably carried by the outer end of said coil and engageable in said groove for holding said core in valve opening position, a releasing solenoid coil, a core slidably in said releasing solenoid coil, and a bell-crank connection between said latter core and said bar, and a spring constantly urging said latter core outwardly of said releasing solenoid coil, said latter spring also biasing said bell-crank and latching bar toward latching position.

55 2. In a valve structure as set forth in claim 1 wherein said latter named core includes a slotted stem and said latching bar is slotted, said bell-crank loosely engaging in said slotted stem and the slot of said bar.

60 JOHN HARDING, JR.
